UNITED STATES PATENT OFFICE

2,414,988

IRONING BOARD ACCESSORY

Ruth Ullberg, Chicago, Ill.

Application August 8, 1944, Serial No. 548,539

2 Claims. (Cl. 38—111)

1

My invention relates to ironing board accessories, and more particularly to receptacles for the overhanging or pendent portions of garments or other articles being ironed to save them from touching the floor and becoming soiled, and my main object is to provide a receptacle for this purpose which utilizes both the ironing board and the usual accessory clothes basket as supports to secure an extensive spread of the receptacle.

A further object of the invention is to construct the novel receptacle in the form of a sheet with unique tie means for securing it to the ironing board and clothes basket.

Another object of the invention is to design it along lines of simplicity and durability.

An important object of the invention is to form the receptacle in one unit for quick handling and to save the loss or misplacement of parts.

With the above objects in view and any others which may suggest themselves from the description to follow, a better understanding of the invention may be had by reference to the accompanying drawing, in which—

Fig. 1 is a side elevation of the receptacle as applied to the ironing board and clothes basket;

Fig. 2 is an enlarged section on the line 2—2 of Fig. 1;

Fig. 3 is a plan view of the receptacle alone; and

Fig. 4 is an enlarged detail section on the line 4—4 of Fig. 2.

Referring specifically to the drawing, 10 denotes a typical foldable ironing board formed with rear legs 11 and a diagonal center leg 12 extending to the front. A conventional clothes basket is shown at 13, its position for the present purpose being crosswise in front of the ironing board.

The receptacle for the overhanging or pendent portions of the garments or other articles being ironed is in the form of a sheet 14 of durable cloth, fabric or other material spread in horizontal position under the ironing board some eight to ten inches above the floor.

The sheet 14 is formed with a rear hem 15 closed at both ends to provide a permanent pocket for a wooden cross-rail 16. The rear portion of the sheet is interrupted by a pair of narrow cutouts 17; and from the outer sides of these pairs of short tapes 18 are extended.

The sheet 14 is also formed with long hems 19 at the sides, these hems being closed at the rear and open in front. Long tapes 20 are housed in the hems 19, being secured at their

2

rear ends to the hem material and extending from the front of the sheet as indicated at 21.

The front of the sheet 14 is made with a transverse hem 22 which is open at both ends. Tapes 23 are lodged in each half of this hem, the inner ends of the tapes being made fast to the hem material while the outer portions extend from the front of the sheet as indicated at 24.

The sheet 14 is made with a longitudinal, oblong opening 25 in the center toward the front.

In the application of the receptacle to the ironing board, the cut-outs 17 are designed to receive the lower portions of the rear legs 11, as shown in Fig. 2. Now the tapes 18 are gathered around the respective legs 11 and tied as indicated at 26, this action drawing the rail 16 firmly against the legs 11 and fixing the position of the rear portion of the receptacle in respect to the ironing board. Also, the tapes 18, originating on the outer sides of the cut-outs 17, serve to draw the sheet taut across the space between the legs 11.

The opening 25 affords the passage of the diagonal leg 12 through the receptacle and is sufficiently long for ample clearance in this respect. The frontal portion of the receptacle is secured by tying the tape ends 21 and 24 in pairs to the handles 27 of the clothes basket 13, as clearly indicated in Fig. 2. The frontal corners of the sheet are cut on a bias, as seen at 28, to afford sufficient separation for the issuing tapes.

It is understood that the ties of the receptacle to the ironing board legs 11 will be at about the same level as those to the basket handles 27, so that the receptacle will be suspended like a net underneath the ironing board with the center sagging somewhat, as indicated in Fig. 1. This figure shows that the receptacle is fully as long as the ironing board, while Fig. 2 indicates that the receptacle is of ample width to catch any sleeves, legs or other garment portions which may overhang or depend from the sides of the ironing board, retaining such parts from contacting the floor or being stepped upon by the user of the ironing board. At the same time, the receptacle is sufficiently elevated from the floor to be out of the way of the operator's feet.

In fact, since the sides of the receptacle are only reinforced by the internal tapes 20, they are readily yieldable in case they are engaged at times by the operator's ankles, this action incidentally helping to raise the sides of the receptacle and more fully guard garment portions retained in the same. The use of the clothes

basket as a frontal support for the receptacle is a benefit from the viewpoint that the clothes basket is a necessary adjunct to the ironing board and in the present case not only forms a frontal support for the receptacle, but also makes possible a maximum length for the same in a zone otherwise occupied only by the clothes basket. The receptacle thus forms an efficient intermediary between the ironing board and the clothes basket.

While I have described the invention along specific lines, various minor changes or refinements may be made therein without departing from its principle, and I desire to consider such changes and refinements as coming within the scope and spirit of the appended claims.

I claim:

1. A receptacle for overhanging portions of articles being pressed on a conventional foldable ironing board, comprising a sheet extending longitudinally under the ironing board at a level above the floor, the rear end of the sheet having a pair of laterally-spaced cut-outs for the passage of the lower portions of the rear ironing board legs, tie means from said rear end around said portions, and other means to support the front of the sheet, said rear end being formed

as a transverse hem interrupted by said cut-outs, and a rail lodged in the hem along said end and with the portions exposed by said cut-outs in engagement with said leg portions.

5 2. A receptacle for overhanging portions of articles being pressed on a conventional ironing board, comprising a sheet extending longitudinally under the ironing board at a level above the floor, means to suspend the rear portion of the sheet from the rear legs of the ironing board, the forward portion of the sheet having an opening for the passage of the diagonal leg of the ironing board, and other means carried by the sheet to support the frontal portion thereof from the handles of a conventional clothes basket positioned crosswise in front of the ironing board, said means comprising hems in the sides of the sheet, tapes in the hems secured in the rear ends thereof and issuing from the front ends 10 of the hems, a transverse frontal hem in the front end of the sheet, and other tapes secured in the center of said frontal hem and issuing from the outer ends thereof, the issuing tapes forming pairs at the sides of the sheet to constitute said means by being tied to the respective clothes basket handles.

RUTH ULLBERG.
